UNITED STATES PATENT OFFICE.

CHARLES AGATSTEIN AND LEWIS SILVER, OF PHILADELPHIA, PENNSYLVANIA.

GAME BOARD OR TABLE.

Application filed January 21, 1922. Serial No. 530,798.

To all whom it may concern:

Be it known that we, CHARLES AGATSTEIN and LEWIS SILVER, citizens of the United States, residing at Philadelphia, in the county of Philadelphia and State of Pennsylvania, have invented new and useful Improvements in Game Boards or Tables, of which the following is a specification.

Our invention relates to a new and useful improvement in game boards or tables, and has for its object to so construct such a table as to provide for the playing of one or more amusing games by requiring a certain amount of skill yet may be played by persons of relatively small skill with great interest.

A further object of our invention is to provide in combination with such a board or table receptacles for the cue balls and scoring pegs used in playing a game.

With these ends in view, this invention consists in the details of construction and combination of elements hereinafter set forth and then specifically designated by

the claims.

In order that those skilled in the art to which this invention appertains, may understand how to make and use the same, we will describe its construction in detail, referring by numerals to the accompanying drawings forming a part of this application, in which:

Fig. 1, is an isometrical view of a board made in accordance with our improvement.

Fig. 2, is a section at the line 2—2 of Fig. 1.

Fig. 3, is a detail view of a cue adapted to be used in playing the game.

Fig. 4, is an isometrical view of the quadrangle frame for placing the object balls in proper position upon the board.

Fig. 5, is a fragmental perspective showing a modified form of constructing the runways for the cue balls.

In carrying out our invention as here embodied, 1 represents the board supported upon the ledges 2, the latter having recesses or compartments 3 therein for the reception of the cues 15 used in playing a game and in order that these receptacles may be closed we provide the swinging doors 4 which are pivoted at 5 and adapted to swing across the exposed ends of the ledges there-

by closing the receptacles as will be readily understood.

6 represents a compartment located beneath the board which also may be closed by a door similar to those just described, pivoted at 6' so as to swing across the opening to the receptacle. This receptacle is adapted to receive the balls when the game is not being played.

Upon the upper surface of the board is located a cage 7 through which gaps 8 are formed for the purpose hereinafter set forth and within this cage are formed a series of depressions or pockets 9 in the upper end of the board which pockets may be distinguished from each other by various colors or by numbers, letters or other designations. Leading from each corner of the board to one of the gaps in the cage is a runway 10 which gradually increases in width from the corner of the board to the gap as clearly shown in Fig. 1. These runways are intended to give the cue balls a general direction when being shot into the cage.

11 represents a quadrangle frame which is utilized for placing the object balls 12 in the center of the cage and in such position that when the frame is removed from around the balls the balls at each angle of the nest will be located opposite one of the gaps in the cage.

13 represent small holes arranged in series for the reception of suitable pegs whereby the score of the game may be accurately and conveniently kept after the manner of a cribbage board.

When playing one of the games in which the board is especially adapted the balls 12 are nested as before described in the center of the cage; a cue ball 14 of smaller diameter than the object balls is placed at the outer end of one of the runways 10 and one of the players manipulating the cue projects this ball along the runway with such force as to scatter the object balls and these object balls if too large to pass through the gaps in the cage a certain number if not all of them will ultimately fall into the pockets 9 and the score thus gained is then registered by the changing of a counting peg in a series of holes 13.

On account of each of the runways widening toward the cage a certain amount of

skill may be exercised in shooting the cue ball so as to scatter the object balls to more effectually cause the latter to fall within the pockets yet the leeway allowed for this exercise of skill is sufficiently limited to enable persons of little or no skill to gain great amusement in playing the game.

While the runways 10 may be formed by grooving the upper surface of the board 10 they may also be formed by securing strips 15 upon the board as indicated in Fig. 5.

While our improved game board is especially adapted for the use of young persons and when constructed for such use is preferably of the form shown in the drawings, but may be utilized for older persons or for tournament purposes in which case the board may be mounted upon suitable legs giving it the effect of a table and the runways may be further widened at their inner ends so as to provide for the exercise of greater skill and thereby give the game the same general scope of pool or pocket billiards.

It is obvious that a single object ball may be placed in the center of the cage the player attempting to so strike this single object ball with the cue ball as to cause it to fall into a particular pocket such a use 30 of the game would require as great or more skill as the playing of billiards.

Of course we do not wish to be limited to the exact details of construction as herein shown as these may be varied within the 35 limits of the appended claims without departing from the spirit of our invention.

Having thus fully described our invention, what we claim as new and useful is:—

1. A game board comprising in combination, a rectangular board having depressed trough-like runways located on the diagonals of said board and leading from the corners toward the center thereof, said central portion of the board having pockets formed therein, and a cage enclosing the central portion of the board with gaps aligning with the runways. 40

2. A game board having a portion of its upper surface enclosed in a cage, said cage having gaps therein, said board provided with trough-like runways leading from the outer portions of the board to said gaps, said runways gradually increasing in width 50 toward the gaps.

3. A game board comprising in combination, a rectangular board having depressed trough-like runways located on the diagonals of said board and leading from the corners toward the center thereof, said runways gradually increasing in width toward 55 their inner ends and having their bottom walls below the surface of the board, said central portion of the board having pockets formed therein and arranged in sets, each set including a plurality of pockets, and a cage enclosing the central portion of the board with the pockets therein, said cage 60 having gaps aligning with the runways.

In testimony whereof, we have hereunto affixed our signatures.

CHARLES AGATSTEIN.
LEWIS SILVER.
